UNITED STATES PATENT OFFICE

153,000

DESIGN FOR A WALL FIXTURE

Rayburn D. Mehlhaff, Lodi, Calif.

Application April 12, 1947, Serial No. 138,331

Term of patent 3½ years

(Cl. D35—3)

To all whom it may concern:

Be it known that I, Rayburn D. Mehlhaff, a citizen of the United States, residing at Lodi, in the county of San Joaquin and State of California, have invented a new, original, and ornamental Design for Wall Fixture, of which the following is a specification, reference being had to the accompanying drawing, forming a part thereof.

The figure on the drawings is a perspective view of a wall fixture, showing my new design.

I claim:

The ornamental design for a wall fixture, as shown.

RAYBURN D. MEHLHAFF.
